(57) **CLAIM**

The ornamental design for a leisure chair as shown and described.

DESCRIPTION

FIG. 1 is a first perspective view of a chair showing our new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view, shown in an environment of use.

The broken lines in FIG. 9 are for the purpose of illustrating portions of the using environment that form no part of the claimed design.
